UNITED STATES PATENT OFFICE.

BEN F. O'BRYANT, OF COLLINSVILLE, ALABAMA, ASSIGNOR OF ONE-HALF TO WARREN HARPER, OF COLLINSVILLE, ALABAMA.

BALANCE-VALVE.

No. 910,225.

Specification of Letters Patent.

Patented Jan. 19, 1909.

Application filed March 11, 1908. Serial No. 420,408.

To all whom it may concern:

Be it known that I, BEN F. O'BRYANT, a citizen of the United States, and a resident of Collinsville, in the county of Dekalb and 5 State of Alabama, have invented a new and Improved Balance-Valve, of which the following is a full, clear, and exact description. The object of the invention is to provide a new and improved balance valve, more 10 especially designed for use in locomotive engines, and arranged to insure an easy movement of the valve when the engine is running or dead, and without danger of bonding, and to allow of conveniently and 15 quickly replacing a worn out bushing in which the controlling piston valve travels.

The invention consists of novel features and parts and combinations of the same, which will be more fully described herein- 20 after and then pointed out in the claims.

A practical embodiment of the invention is represented in the accompanying drawings forming a part of this specification, in which similar characters of reference indicate cor- 25 responding parts in all the views.

Figure 1 is a longitudinal sectional elevation of the improvement as applied; Fig. 2 is a transverse section of the same on the line 2-2 of Fig. 1; Fig. 3 is an inverted plan 30 view of the steam chest, the heads being removed; Fig. 4 is a side elevation of the piston valve; Fig. 5 is a longitudinal sectional elevation of the steam chest, the heads being removed, and Fig. 6 is an end view of 35 the steam chest.

The steam chest A is secured by bolts B to the engine cylinder C of the usual construction, and having the cylinder ports a and b and the exhaust port c. In the steam 40 chest A is arranged a transversely-extending integral partition D, preferably made arch shaped, as plainly indicated in Fig. 2, so as to form with the inner wall of the steam chest A, longitudinally-extending channels 45 A', to connect the ends of the steam chest A with each other. The partition D forms the valve chest proper and is provided with a longitudinally-extending bore E, into which fits a bushing F, projecting with its ends 50 slightly beyond the faces of the arch-shaped partition D, as plainly indicated in Figs. 1, 3 and 5. In the bushing F is mounted to reciprocate the piston valve G, mounted to turn loosely on and moving with the valve 55 stem H extending through a suitable stuffing

box I in the head J for closing one end of the steam chest A, the other end of the steam chest being closed by a head J'. The valve stem H is connected in the usual manner with the valve gear, for imparting a reciprocating motion to the piston valve G. The piston valve G is provided with piston heads G', G², having suitable packing rings K in their peripheral faces, and the said piston heads G', G² are integrally connected with each other by the reduced middle portion G³, mounted on the stem H, and having a central channel G⁴ connected at its ends by branch channels G⁵, G⁶ with the hollowed-out ends G⁷, G⁸ of the piston heads G', G², as plainly indicated in Fig. 1. On the stem H is secured or formed a collar H' abutting against the left-hand end of the middle portion G³ within the hollowed-out or recessed end G⁷, and on the terminal of the stem H 75 screw nuts H² extending within the recessed end G⁸ and abutting against the right-hand end of the middle portion G³, to connect the piston valve G with the stem H, but to allow the piston valve G to turn loosely on the stem so as to wear evenly. By having the channel G⁴ and the branch channels G⁵, G⁶, steam can circulate from one end of the steam chest to the other, in addition to the channels A' above referred to. 85

The cylinder ports a and b register with the ports d and e formed in the partition D, which is also provided with a port f in register with the exhaust port c. The ports d, e and f in the partition D register with corresponding ports g, h and i formed in the bushing F, and the bushing ports are controlled by the piston heads G', G², so as to control the steam passing to and from the cylinder C in the same manner as in engines 95 provided with the ordinary slide valve.

In order to lubricate the cylinder, the lubricant is passed by a pipe L into the bushing F near the ends thereof, the said pipe L being connected with a suitable oil 100 cup L', as indicated in Fig. 1.

A relief valve N of any approved construction is connected with the steam chest head J', and the joint between the bottom face of the steam chest A and the corresponding face of the cylinder C is rendered steam-tight by interposing packing wires O, as plainly shown in Figs. 1 and 2. The steam enters the steam chest A by the usual channels P formed in the cylinder C and 110

connecting with the ends of the steam chest A adjacent to the faces of the partition D, and by the arrangement described the steam can readily pass from one end of the steam chest A to the other by way of the channels 5 G⁴, G⁵, G⁶ and A', as before explained. Now when the engine is running, the piston valve G controls the admission and exhaust of the steam to and from the cylinder C, and 10 by having the valve G in the form of a piston valve, it is evident that it is completely balanced, and consequently the valve reciprocates easily within the bushing F. In case the bushing F becomes worn out, it 15 can be readily replaced by a new one without discarding the steam chest A.

The usual slide valve now used in locomotive engines, can be readily replaced when worn out by the arrangement above described and shown in the drawing, that is, the locomotive engines can be quickly refitted with new valves whenever deemed necessary and hence the locomotive is again ready for service in a short time.

Having thus described my invention, I claim as new and desire to secure by Letters Patent:—

1. An engine provided with a steam chest, having a transverse partition provided with 30 a longitudinal bore and with longitudinal channels connecting the ends of the steam chest with each other, a bushing fitting the said bore, the said bushing and partition having registering ports registering with the ports of the engine cylinder, and a piston 35 valve mounted to slide in the said bushing and having spaced piston heads for controlling the said ports and longitudinal openings for the passage of steam there- 40 through.

2. An engine provided with a steam chest, having a transverse partition provided with

a longitudinal bore, said partition being arch-shaped and forming with the inner wall of the steam chest longitudinal passages 45 connecting the ends of the steam chest with each other, a piston valve in said bore, and a stem for moving the piston valve forward and backward and on which stem the said piston valve is mounted to turn freely. 50

3. An engine provided with a steam chest, having a transverse partition provided with a longitudinal bore and with longitudinal channels for connecting the ends of the said steam chest with each other, a bushing fitting the said bore, the said bushing and partition having registering ports registering with the ports of the engine cylinder, and a piston valve mounted to slide in the said bushing 55 and having spaced piston heads for controlling the said ports a central channel and branch channels leading therefrom out through the ends of the piston heads.

4. An engine provided with a steam chest, having a transverse partition provided with 60 a longitudinal bore, a bushing fitting the said bore, the said bushing and partition having registering ports registering with the ports of the engine cylinder, and a piston valve mounted to slide in the said bushing 70 and having spaced piston heads for controlling the said ports, the said piston valve being mounted to turn freely on its stem, and the said piston valve having longitudinal openings, hollowed out ends, a central channel and branch channels leading therefrom 75 out through said ends.

In testimony whereof I have signed my name to this specification in the presence of two subscribing witnesses.

BEN F. O'BRYANT.
